UNITED STATES PATENT OFFICE.

ADOLPH BALLENBERG, OF NEW YORK, N. Y.

CASTER.

1,169,001.

Specification of Letters Patent. Patented Jan. 18, 1916.

Application filed September 17, 1915. Serial No. 51,139.

To all whom it may concern:

Be it known that I, ADOLPH BALLENBERG, a citizen of the United States, and residing at New York, in the county of New York and State of New York, have invented certain new and useful Improvements in Casters, of which the following is a specification, such as will enable those skilled in the art to which it appertains to make and use the same.

This invention relates to casters and particularly to devices of this class designed for use in connection with articles of furniture and other articles having tubular legs, and the object of the invention is to provide an improvement in this class of devices whereby the casters are made detachable and are held in position by spring clamp devices which are automatic in operation, whereby the casters may be quickly and easily attached or detached whenever necessary; a further object being to provide casters with attaching devices of the class specified, which may be applied to tubular or hollow legs or supports for articles of furniture or other articles and which are cylindrical in cross section, square or octagonal in form.

The invention is fully disclosed in the following specification, of which the accompanying drawing forms a part, in which the separate parts of my improvement are designated by suitable reference characters in each of the views, and in which:

Figure 1 is a sectional side view of a tubular leg or support and showing my improvement; Fig. 2 a section on the line 2—2 of Fig. 1; Fig. 3 a section on the line 3—3 of Fig. 2; Fig. 4 a plan view of a spring clamp plate which I employ; and, Fig. 5 a side view of a spring clamp formed from the plate shown in Fig. 4.

In the accompanying drawing, I have shown at *a* a leg or support for an article of furniture such as a bed, or any other article, and I have also shown at *b* a caster, comprising a yoke member *b*², a roller *b*³ mounted in the yoke member and a pintle *b*⁴ connected with the cross head portion *b*⁵ of the yoke member *b*.

In the practice of my invention, as shown in the drawing, I mount on the pintle *b*⁴ a disk-shaped plate *c* on which the leg or support *a* rests and said disk-shaped plate is preferably provided with a raised central portion *c*². I also provide two similar spring

clamp devices *d*, each of which comprises a horizontal top portion *d*², a horizontal bottom portion *d*³ and an inwardly curved U-shaped or V-shaped central portion *d*⁴, as clearly shown in Figs. 2 and 5, and the spring clamp devices *d* are formed from oblong spring plates one of which is shown at *d*⁵ in Fig. 4. This plate is provided with an oblong central aperture *d*⁶ and with opposite end oblong apertures *d*⁷, the end apertures *d*⁷ being shorter in their longitudinal dimensions than the central aperture *d*⁶, and these apertures form corresponding apertures in the top, bottom and central portion of the spring clamp devices *d*, as clearly shown in Figs. 2 and 5.

In practice, the spring clamp devices *d* are placed together with the top and bottom members overlapping and the central portions abutting as shown at *d*⁸ in Figs. 1, 2 and 3, and the pintle *b*⁴ of the caster is passed upwardly through the apertures *d*⁷, *d*⁶ and *d*⁷, and the top end or head of the pintle is riveted as shown at *b*⁶ to hold the parts together, and with this construction the spring clamp devices *d* are connected with the pintle *b*⁴ of the caster and will remain therewith when said caster is detached.

The apertures *d*⁷ in the top and bottom parts of the spring clamp devices *d* are of greater dimensions than the transverse dimensions of the pintle *b*⁴, and the central slots *d*⁶ in the said clamp devices *d* are also of greater dimensions than the pintle, and this permits of slight lateral movement of the clamp devices *d* on the pintle when said clamp devices and the pintle are inserted into the leg or support *a*, and the abutting of the clamp devices, or the central portions *d*⁸ thereof adds to the elasticity of said spring clamp devices as does also the double or looped forms of the end portion of said clamp devices, and when it is desired to connect the caster with the leg or support, all that is necessary is to force the pintle with the spring clamp devices connected therewith into the bottom of the leg or support, until said leg or support rests on the disk-shaped plate *c* as clearly shown in Figs. 1 and 2. In this operation, the spring clamp devices *d* present four corners both at the top and bottom, or eight corners in all, which press firmly on the inner wall of the leg or support *a*, as clearly shown at *e* in Fig. 3, and this securely binds the caster to the leg or

support and prevents any lateral movement of the caster in or on the leg or support, or any movement of the said leg or support on the caster.

In the accompanying drawing, I have shown only a tubular leg or support, or a leg or support that is circular or cylindrical in cross section, but it must be understood that my improved caster attaching device or devices will operate in the same way in a square leg or support, or in an octagonal leg or support.

I am aware that casters of the class described have heretofore been detachably connected with the hollow or tubular legs of articles of furniture, or other articles, by means of spring clamp or attaching devices connected with the casters and inserted into, or forced into said legs or supports but such devices as heretofore made have differed from mine in form, construction and operation and have usually permitted lateral movement of the caster in or on the leg, or support, or lateral movement of the leg or support on the caster whereas with my improvement no lateral movement of the caster is possible, and no rattle of the parts, or noise of any kind is possible in the movement of furniture or other articles, the legs or supports of which are provided with my improved casters.

Having fully described my invention, what I claim as new and desire to secure by Letters Patent, is:—

1. A caster for use in connection with a tubular or hollow leg or support, said caster being provided with a pintle on which is loosely mounted a plate adapted to bear on the bottom of the leg or support, and two separate spring devices mounted on the opposite sides of the pintle, said spring devices being provided with inwardly directed top, bottom and central members, the top and bottom members overlapping and the central members abutting, and said top, bottom and central members being provided with apertures through which the pintle loosely passes, and the top and bottom portions of said spring devices being adapted to bear at dif-

ferent points on the inner walls of the leg or support.

2. A caster for use in connection with the hollow leg or support for articles of furniture or other articles, said caster being provided with a pintle on which is loosely mounted a plate which bears on the bottom of the leg or support, and the pintle being provided with two oppositely arranged spring devices having top, bottom and central portions through which the pintle loosely passes and which are adapted to bear at different points on the inner walls of the leg or support at the top and bottom of the pintle.

3. A caster for use in connection with a leg or support for an article of furniture or other article, said caster being provided with a pintle, two oppositely arranged spring devices loosely mounted on said pintle and provided with outwardly and inwardly directed loops and the top and bottom loops of which are adapted to bear on the inner walls of the leg or support and the other loops being adapted to form central bearings for said spring devices.

4. A caster for use in connection with a leg or support for an article of furniture or other article, said caster being provided with a pintle, two oppositely arranged spring devices loosely mounted on said pintle and each provided with three loops, two of said loops of each spring device being adapted to bear on the inner walls of the leg or support while the other loops bear on each other.

5. An attaching device for use in connection with a leg or support for an article of furniture or other article, said attaching device presenting four spring loops which bear on the inner walls of the leg or support.

In testimony that I claim the foregoing as my invention I have signed my name in presence of the subscribing witnesses this 15th day of September 1915.

ADOLPH BALLENCERG.
